UNITED STATES PATENT OFFICE.

JOHN D. ROSS AND STANLEY D. ROSS, OF VANCOUVER, BRITISH COLUMBIA, CANADA.

ROCK PULVERIZER.

Application filed January 17, 1921. Serial No. 437,853.

To all whom it may concern:

Be it known that we, JOHN D. Ross and STANLEY D. Ross, citizens of the Dominion of Canada, residing at Vancouver, in the 5 Province of British Columbia, Canada, have invented certain new and useful Improvements in Rock Pulverizers, of which the following is a specification.

This invention relates to a rock pulverizer 10 of that class wherein the crushing is effected by a series of balls driven around a circular grooved track, by a similarly grooved ring resting on the upper sides of the balls, and rotated by any suitable means.

15 Our improvements are directed to a means for supplementing the crushing pressure of the balls due to the weight on them, and for varying that supplementary pressure to meet the requirements of the ore, without applying additional weight; to a means for supporting the rotatable ball driving ring against the pull of the belt or chain by which it is driven, and to a means for re-passing the pulp through a succession of ball 20 races.

25 The invention also includes other subsidiary features of improvement to which attention will be drawn in the following specification, which fully describes the invention, 30 reference being made to the drawing by which it is accompanied, in which:

Fig. 1 is a vertical section of the mill in the axis of rotation.

Fig. 2, a plan of the same, portions being 35 removed to show underlying parts, and

Fig. 3 is a vertical section of a modified form of the device.

The device comprises a base ring 2, preferably carried on three supports 3, so as to 40 be stable on a possibly uneven surface. Within this base ring 2 is set a lower ring 4 having a circumferential track groove for a series of crushing balls 5. The central space within the grooved ring 4 is closed by 45 a flattened conical plate 6 secured in any convenient manner, preferably by a central bolt 7 to a bar 8 extending diametrically across the underside of the ring 4.

On the balls 5 of the ring 4 is an upper 50 ring 9 grooved in the same manner as 4 to retain the balls, and secured in any convenient manner to the inner edge of this upper ring 9 is a driving cylinder 10 to the upper edge of which is secured a sprocket drive 55 ring 11. The drive ring 11, cylinder 10 and

upper grooved ring 9 are secured together by bolts 12, each ring 11 and 9 being socketed on the ends of the cylinder with key pins 13 fitting in notches in the cylinder ends to retain them in rotational connection, leaving to the bolts the work of holding the rings together on the cylinder.

The upper face of the sprocket ring 11 is grooved to receive a race of balls 14 and on these balls rests a presser plate 15 which is 65 connected to the base ring 2 by hinged bolts 16, each having a coiled spring 17 between the presser ring and the nuts 18 by which the pressure of these springs is regulated to what is required to supplement the weight on 70 the balls 5 to give the desired crushing effect between the balls 5 and the grooved rings 4 and 9.

The sprocket ring 11 and its connected parts are rotated by a chain 19 from any convenient source of power and the driving tension of the chain is withstood by a link 20, connected to the ring 15 opposite the driving chain 19, and to a standard 21 secured to and upwardly projecting from the base 80 ring 2.

Secured to the outer edge of the lower grooved ring 4 and upwardly projecting to above the balls 5 is a border ring 22 of sheet metal, and secured to and upwardly projecting from the upper edge of this ring 22 is a ring screen 23 of fine wire gauze through which the pulverized rock will pass when of the required fineness.

Secured to the lower edge of the ring 22 90 where it is connected to the lower grooved ring 4 is a ring plate 24 which with the ring plate 22 forms an annular gutter 25 through which the screened pulp is delivered to the pipe 26 for such further treatment as may be 95 necessary.

Adjacent the centre of the conical centre plate 6 a pipe 31 delivers a sufficiency of water to wash the rock as pulverized from the groove of the plate 4.

In use, the broken rock is delivered through a spout 27 to within the cylinder 10 and falling on the conical plate 6 passes to between the balls 5 as they roll round the grooves in the rings 4 and 9. As the rock is 105 crushed to the required fineness, it is washed through the screen 23 into the gutter 25 and is delivered through the pipe 26.

As the border ring 22 is carried up above the bearing of the ring 9 on the balls 5; 110

the pulp is retained within the track of the balls in the rings 4 and 9 until the pulp is fine enough to be carried away in the water flow through the screen 23.

5 Although this is the case in the machine illustrated, we do not desire to be confined to this feature as the screen 23 may be lowered or even removed altogether and the pulp be allowed to flow over the edge of 10 the ring 4 into a gutter for delivery to other treatment, in which case the chain 19 and its driving sprocket may be closer to the ring 9.

Around the bottom of the groove in the 15 ring 4 is a channel 28, which at intervals apart is connected by radial pipes 29 to a common delivery 30 closable with a plug.

The channel 28 and its connected pipes 29 30 are charged with quicksilver with which 20 any free gold released by the crushing will amalgamate. The inner side of the border ring 22 may also be silvered and amalgamated to catch any free gold.

The essential features of our improvement 25 reside in the means for applying a spring pressure upon the upper ring 9 and the balls 5 whereby the crushing effort may be varied at will to suit changed requirements: Further in the means 20 21 for sustaining the pull of the driving chain 19 whereby wear of the ball grooves in the 30 rings 4 and 9 to one side may be avoided.

Fig. 3 shows a modification wherein the 35 size of the balls 14, which support the presser plate 15, is enlarged that they may serve as crushing balls. In this case the upper side of the ring 9, instead of the gear ring 11, is grooved to receive the balls 14, the presser ring 15 being applied to those 40 balls by the springs 17 as before; and the gear ring 11 is, as before, connected to the ring 9 by the cylinder 10.

The border ring 22 is carried slightly above 45 the bearing of the upper tier of balls in the presser plate 15, so that the pulp as delivered from outside the ring of balls 5 is constrained to rise and come under the action of the ring of balls 14 before delivery.

The pulp will thus be subjected to the 50 pulverizing action of two rings of balls, the lower one effecting the primary crushing and the crushed pulp carried by the water flow will pass through the upper tier. It is noteworthy that in such cases any material that is insufficiently pulverized to rise 55 with the flow of water will again come under the crushing action of the lower balls 5, leaving only the finer material to pass through the upper ring.

60 The mill is simple to manufacture, is not liable to derangement and is effective in use. The provision for spring-loading the pressure on the crushing balls enables the weight to be reduced for transportation.

65 The manner of resisting the tendency of

the driving effort to pull the rings and grinding balls toward the side from which the driving effort is exerted is advantageous in maintaining more uniform wear of the ball rings, which alone are depended upon 70 to maintain concentric movement. The addition of a second series of grinding balls enables the pulp to be more finely pulverized, for which there is a growing requirement on the part of mining engineers, while 75 the provision of a means whereby the free gold as released from the rock may be at once amalgamated in the lowest part of the mill relieves the subsequent treatment of the pulp of the recovery of that gold. 80

Having now particularly described our invention, we hereby declare that what we claim as new and desire to be protected in by Letters Patent, is:

1. A rock pulverizer, comprising the combination with a suitable base, of a ring having a circumferential groove, supported by the base, a series of crushing balls in the groove of the ring, a second ring circumferentially grooved to rest on the balls in the 90 first named groove, a driving wheel connected to the upper ring, said driving wheel having a circumferential groove in its upper side, a series of balls within the groove, a presser plate having a circumferential 95 groove adapted to rest on the upper series of balls, resilient means applied to the presser plate for pressing the balls in the groove, means for delivering the rock to be crushed to within the lower ring of 100 balls, and means for delivering the crushed rock from the outer side of the ring.

2. A rock pulverizer, comprising the combination with a suitable base, of a ring having a circumferential groove, supported by 105 the base, a series of crushing balls in the groove of the ring, a second ring circumferentially grooved to rest on the balls in the first named groove, a driving wheel connected to the upper ring, said driving wheel 110 having a circumferential groove in its upper side, a series of balls within the groove, a presser plate having a circumferential groove adapted to rest on the upper series 115 of balls, resilient means applied to the presser plate for pressing the balls in the groove, means for delivering the rock to be crushed to within the lower ring of balls, and means for screening the crushed rock and for delivering the screened material. 120

3. A rock pulverizer, comprising the combination with a suitable base, of a ring having a circumferential groove, supported by the base, a series of crushing balls in the groove of the ring, a second ring circumferentially grooved to rest on the balls in the 125 first named groove, a driving wheel connected to the upper ring, said driving wheel having a circumferential groove in its upper side, a series of balls within the groove, 130

a presser plate having a circumferential groove adapted to rest on the upper series of balls, resilient means applied to the presser plate for pressing the balls in the groove, means applying to the presser plate for sustaining the pull of the driving means, means for screening the crushed material and for delivering the screened material.

4. A rock pulverizer, comprising the combination with a suitable base, of a ring having a circumferential groove, supported by the base, a series of crushing balls in the groove of the ring, a second ring circumferentially grooved to rest on the balls in the first named groove, a driving wheel connected to the upper ring, said driving wheel having a circumferential groove in its up-

per side, a series of balls within the groove, a presser plate having a circumferential groove adapted to rest on the upper series of balls, rods between the base of the machine and the presser plate, said rods having nuts threaded on their upper ends, springs between the nuts and the presser plate, means for connecting the presser plate to a stationary part of the machine opposite the pull of the driving means, means for delivering broken rock to within the ring of crushing balls, and means for delivering the crushed rock from the machine. 30

In testimony whereof we affix our signatures.

JOHN D. ROSS.

STANLEY D. ROSS.
